UNITED STATES PATENT OFFICE.

ROBERT LUNGSTRAS AND PAUL LUNGSTRAS, OF ST. LOUIS, MISSOURI.

PROCESS FOR CLEANING GLOVES.

1,100,436.

Specification of Letters Patent. Patented June 16, 1914.

Application filed July 16, 1913. Serial No. 779,345.

To all whom it may concern:

Be it known that we, ROBERT LUNGSTRAS and PAUL LUNGSTRAS, citizens of the United States, residing at St. Louis, State of Missouri, have invented certain new and useful Improvements in Processes for Cleaning Gloves, of which the following is a specification.

This invention relates to processes or methods for extracting the accumulation of grease, dirt, perspiration, stains, etc., found upon gloves, particularly the finger tips of kid or leather gloves, which have been worn for any considerable period of time; and 15 has for its prime object to afford a process not merely simple and inexpensive, but, also, more rapid, satisfactory and effective than that disclosed in the patent to Robert Lungstras, a party to this application, No. 20 986,072, dated March 7, 1911.

In the earlier methods of cleaning gloves the article would first be soaked in a volatile dissolving or cleaning fluid, next placed on forms, then rubbed by hand with a bristle brush moistened with the dissolving fluid and finally rinsed in a receptacle containing fluid (i. e. clean) dissolving fluid. Subsequently came attempts to eliminate the large expenditure of time and manual labor entailed in the 30 earlier process described and machines were introduced comprising bristle brushes which revolved or otherwise moved in a cleansing fluid in contact with the gloves placed in said machines. In some of these mechanical 35 contrivances the brushes referred to were given a reciprocatory or "scrubbing" movement with the idea of more efficaciously cleaning the gloves, while in other types one field or series of brushes was moved in a 40 direction opposite to that given another field or series. Here, also, the gloves were rinsed in fresh cleaning fluid after removal from the machine and the finger tips would then be examined, whereupon it would be found 45 that approximately 75% were insufficiently cleaned and these would be put on a "hand stick" or form and the tips "worked" clean by friction with a moistened brush as in the earlier process. Where the stains were stubborn the glove would be removed from the 50 form and "kneaded" between the fingers of the operator for the three-fold purpose of softening the material, raising the fiber or nap to a slight extent and, primarily, to 55 squeeze out (as it were) the dirt and greasy

deposits, the glove being moist or damp with cleaning fluid while so kneaded.

In the accompanying drawing, in which like numerals refer to like parts throughout the several views, Figure 1 is sectional elevation of one form of apparatus by aid of which our process may be carried out; Fig. 2 a cross-section of the apparatus shown in Fig. 1; Fig. 3 a sectional elevation of another form of apparatus which may be employed with advantage; and Fig. 4 a cross-section of the apparatus shown in Fig. 3.

In the practice of our invention we may employ a cylindrical rotary machine of the character depicted in Figs. 1 and 2, the 70 same comprising a receptacle 1 suspended, by axles 2 affixed to its opposite heads 3, in a substantially air-tight housing 4 and adapted to receive reciprocal rotation or rotation continuously in one direction through 75 the agency of a crank-handle 5 keyed upon one of said axles. It will, of course, be appreciated that other means for imparting motion to said receptacle may be substituted for handle 5, such as a belt and pulley arrangement used in connection with the well-known automatic reversing-gears.

So far as concerns an apparatus by aid of which this process can be carried out, a machine embracing the parts above described 85 and shown in Fig. 1 would suffice to accomplish excellent results, but we have discovered that the use of a machine embracing the features shown in Figs. 3 and 4 will, under certain conditions, give better results 90 than the simpler apparatus. Referring to Figs. 3 and 4 it will be noted that housing 4 is double-jacketed for the provision of a chamber 6 containing pipe-coil 7 which is supplied with hot water or steam from the 95 boiler of an engine, not shown; that receptacle 1 is perforate as at 8; and that pipes 9 and 10 project within the space existing between the inner wall of said housing and the exterior surface of said receptacle. The gloves (or other similar articles) 100 to be cleaned are, preferably, placed in open-mesh bags 11 and mixed therein with a quantity of small sponges 12, a number of such bags so filled being then disposed in receptacle 1. The bags as thus disposed are submerged in a volatile dissolving or cleaning fluid 13, preferably high-grade gasoline, with which is mixed an alkali, preferably 105 caustic potash or ammonia, and a fatty 110

acid, preferably oleic acid (acidum oleicum or hydrogen oleate). If the apparatus shown in Fig. 3 be employed, the doors of the housing having been closed, the air is 5 first exhausted by means of a pump (not shown) connected with pipe 9, an inert gas, preferably nitrogen gas or carbonic gas, is next introduced from any convenient source of supply through pipe 10 and, finally, 10 steam is turned through coil 7 to heat the gasolene. The machine selected having been set in motion, through the agencies before described, the gloves are constantly washed by the gasolene and the oleic acid, being 15 readily soluble in the volatile fluid, is saponified by the alkali and serves to disintegrate the oily deposits and dirt of other character upon the gloves, while the highly important function of the sponges is to 20 scrub the gloves, gently and persistently abrade them and to supply the valued "kneading" operation formerly secured by manual manipulation.

By reference to the prior patent hereinbefore mentioned it will be appreciated that 25 in discovering the adaptability of sponges for use in lieu of "objects 7" forming part of the subject-matter of said patent a valuable advance in this art has been made.

Whereas said "objects" were of "gritty" 30 character adapted to readily wear away in use and, hence, were apt to act too severely upon the gloves and had to be replaced at rather frequent intervals, the sponges now 35 employed are rendered peculiarly firm and tough by the action thereon of the gasolene and thus, while filling the office of said "objects", do not readily wear away in use and are incapable of acting too severely upon the 40 gloves. The abrading effect produced by said sponges, as aforesaid, is gentle in the extreme, but is quite sufficient to remove any dirty nap or glaze in order to expose the underlying comparatively clean "strata" of 45 material and it will be appreciated that the use of a number of bags 11 each containing a quantity of gloves and sponges contributes in no small degree to the success of this process, inasmuch as said bags serve to retain the 50 gloves and sponges in very close relation while the movement of the machine has the effect of constantly throwing one bag against another which results in compressing and forcibly rubbing together the articles contained therein.

We deem it proper to state that while 55 sponges have been found the most satisfactory articles to be used in this process because of their peculiar firmness while under 60 the action of the gasolene, whereby they are enabled to engage and literally scrub the glove surface, yet we do not wish to be understood as limiting ourselves precisely thereto and the right is reserved of employing in lieu thereof any article or material 65

in which lightness in weight is combined with some of the other characteristics of a sponge, as, for example, rough and porous cloth, felt, burlap, canvas or chamois-skin.

What we claim as new and desire to secure 70 by Letters Patent is:—

1. The process of cleaning gloves which comprises the disposition thereof in a cleansing fluid, in imparting motion to the vessel containing said fluid, and in subjecting the gloves in the moving vessel to massage by a plurality of objects of spongy character. 75

2. The process of cleaning gloves which comprises the disposition thereof in a cleansing fluid, in heating said fluid, in imparting motion to the vessel containing said fluid, and in subjecting the gloves in the moving vessel to massage by a plurality of objects of spongy character. 80

3. The process of cleaning gloves which comprises the disposition thereof in a cleansing fluid, in adding to said fluid a fatty acid and an alkali, in imparting motion to the vessel containing said fluid, acid and alkali, and in subjecting the gloves in the moving vessel to massage by a plurality of objects of spongy character. 85

4. The process of cleaning gloves which comprises the disposition thereof in a cleansing fluid, in adding to said fluid a fatty acid and an alkali, in heating said fluid, in imparting motion to the vessel containing said fluid, acid and alkali, and in subjecting the gloves in the moving vessel to massage by a plurality of objects of spongy character. 90

5. The process of cleaning gloves which comprises the disposition thereof in bags submerged in a cleansing fluid, in imparting motion to the vessel containing said fluid, and in subjecting the gloves in the moving vessel to massage by a plurality of objects of spongy character confined in said bags. 95

6. The process of cleaning gloves which comprises the disposition thereof in bags submerged in a cleansing fluid, in heating said fluid, in imparting motion to the vessel containing said fluid, and in subjecting the gloves in the moving vessel to massage by a plurality of objects of spongy character confined in said bags. 100

7. The process of cleaning gloves which comprises the disposition thereof in bags submerged in a cleansing fluid, in adding to said fluid a fatty acid and an alkali, in imparting motion to the vessel containing said fluid, acid and alkali, and in subjecting the gloves in the moving vessel to massage by a plurality of objects of spongy character confined in said bags. 110

8. The process of cleaning gloves which comprises the disposition thereof in bags submerged in a cleansing fluid, in adding to said fluid a fatty acid and an alkali, in heating said fluid, in imparting motion to the vessel containing said fluid, acid and alkali, 115

120

125

and in subjecting the gloves in the moving vessel to massage by a plurality of objects of spongy character confined in said bags.

9. The process of cleaning gloves which comprises the disposition thereof in a cleansing fluid, in exhausting the air from the vessel containing said fluid, in replacing said air with an inert gas, in imparting motion to said vessel, and in subjecting the 10 gloves in the moving vessel to massage by a plurality of objects of spongy character.

10. The process of cleaning gloves which comprises the disposition thereof in a cleansing fluid, in exhausting the air from the vessel containing said fluid, in replacing said air with an inert gas, in heating said fluid, in imparting motion to said vessel, and in subjecting the gloves in the moving vessel to massage by a plurality of objects of 15 spongy character.

11. The process of cleaning gloves which comprises the disposition thereof in a cleansing fluid, in adding to said fluid a fatty acid and an alkali, in exhausting the air 25 from the vessel containing said fluid, acid and alkali, in replacing said air with an inert gas, in imparting motion to said vessel, and in subjecting the gloves in the moving vessel to massage by a plurality of objects of spongy character.

12. The process of cleaning gloves which comprises the disposition thereof in a cleansing fluid, in adding to said fluid a fatty acid and an alkali, in heating said fluid, in exhausting the air from the vessel containing 35 said fluid, acid and alkali, in replacing said air with an inert gas, in imparting motion to said vessel, and in subjecting the gloves in the moving vessel to massage by a plurality of objects of spongy character.

13. The process of cleaning gloves which comprises the disposition thereof in bags submerged in a cleansing fluid, in exhaust-

ing the air from the vessel containing said fluid, in replacing said air with an inert 45 gas, in imparting motion to said vessel, and in subjecting the gloves in the moving vessel to massage by a plurality of objects of spongy character confined in said bags.

14. The process of cleaning gloves which 50 comprises the disposition thereof in bags submerged in a cleansing fluid, in exhausting the air from the vessel containing said fluid, in replacing said air with an inert gas, in heating said fluid, in imparting motion 55 to said vessel, and in subjecting the gloves in the moving vessel to massage by a plurality of objects of spongy character confined in said bags.

15. The process of cleaning gloves which 60 comprises the disposition thereof in bags submerged in a cleansing fluid, in adding to said fluid a fatty acid and an alkali, in exhausting the air from the vessel containing 65 said fluid, acid and alkali, in replacing said air with an inert gas, in imparting motion to said vessel, and in subjecting the gloves in the moving vessel to massage by a plurality of objects of spongy character confined in said bags.

16. The process of cleaning gloves which 70 comprises the disposition thereof in bags submerged in a cleansing fluid, in adding to said fluid a fatty acid and an alkali, in exhausting the air from the vessel containing 75 said fluid, acid and alkali, in replacing said air with an inert gas, in heating said fluid, in imparting motion to said vessel, and in subjecting the gloves in the moving vessel to massage by a plurality of objects 80 of spongy character confined in said bags.
